UNITED STATES PATENT OFFICE.

JOHN H. GOODBODY, OF NEW YORK, N. Y.

DESIGN FOR A BUSTLE.

SPECIFICATION forming part of Design No. 29,558, dated October 25, 1898.

Application filed September 15, 1898. Serial No. 691,044. Term of patent 7 years.

To all whom it may concern:

Be it known that I, JOHN H. GOODBODY, a citizen of the United States, residing in the city of New York, county and State of New York, have invented and produced a certain new and original Design for Bustles, of which the following is a specification, reference being had to the accompanying drawings, forming a part hereof.

- o My invention relates to designs for bustles, more especially to the side or hip sections of such articles; and it consists in a bustle having the shape and configuration substantially as shown in the accompanying drawings, in which—
  - Figure 1 is a view in elevation of a bustle which embodies my design. Fig. 2 is an edge view of one of the side or hip sections as seen from the outside, and Fig. 3 is an edge view of the same section when looked at in the direction of the arrow shown in Fig. 1.

Referring to the drawings, it will be seen that the upper or inner edge of the bustle is defined by a substantially concave line and that the outer or lower edge is defined by a substantially convex line of smaller radius than the inner or upper line and meeting the latter at the extremities of the bustle. Each

side or hip section A is substantially a spherical triangle, as viewed in a line perpendicular to its general plane, one edge, as from a to a' , being concave in a vertical plane, the edge from a' to a^2 being convex in a vertical plane, and the remaining edge from a^2 to a being substantially straight. As seen in edge view in a horizontal plane, the edge from a to a' is concave underneath and the edge from a' to a^2 is a compound curve.

The leading feature of my design is the side or hip section, having one edge concave in both of two planes substantially at right angles to each other and having another or the outer edge convex in one of such planes and compoundedly curved in the other of such planes.

What I claim, and desire to secure by Letters Patent, is—

The design for a bustle, as herein shown and described.

This specification signed and witnessed this 12th day of September, A. D. 1898.

JOHN H. GOODBODY.

In presence of—

A. N. JESBERA,
W. B. GREELEY.
